FOREIGN PATENT DOCUMENTS

GB 2058435 * 7/1997

Primary Examiner—Elizabeth A Albert*Assistant Examiner*—Karen E Eldridge Powers(74) *Attorney, Agent, or Firm*—Brinks Hofer Gilson & Lione(57) **CLAIM**

I claim the ornamental design for a hat strap sleeve, as shown and described.

DESCRIPTION

FIG. 1 is a perspective view of a hat strap sleeve;

FIG. 2 is a front view thereof;

FIG. 3 is a rear view thereof;

FIG. 4 is a side view thereof;

FIG. 5 is a top view thereof; and,

FIG. 6 is a bottom view thereof.

The broken lines shown in the drawings illustrate environmental matter and form no part of the claimed design.
